UNITED STATES PATENT OFFICE.

HOWARD S. BROWN, OF OASIS, UTAH, ASSIGNOR TO PAWLING AND HARNISCHFEGER COMPANY, OF WEST MILWAUKEE, WISCONSIN, A CORPORATION OF WISCONSIN.

EXCAVATING-WHEEL.

1,386,987.

Specification of Letters Patent.

Patented Aug. 9, 1921.

Application filed August 19, 1920. Serial No. 404,505.

To all whom it may concern:

Be it known that I, HOWARD S. BROWN, a citizen of the United States, residing at Oasis, in the county of Millard and State of Utah, have invented certain new and useful Improvements in Excavating-Wheels; and I do declare the following to be a full, clear, and exact description of the invention, such as will enable others skilled in the art to 10 which it appertains to make and use the same.

This invention relates to an improved excavating wheel for use in digging ditches and one object of the invention is to provide 15 an excavating wheel with an improved type of bucket including sections movably mounted for movement into and out of an operative position as the wheel rotates.

Another object of the invention is to so 20 construct the bucket that the movable portions thereof may include the digging or cutting elements and a bottom for the bucket, pressure upon the digging or cutting elements during the filling of the bucket serving to retain the bottom in an operative 25 position.

Another object of the invention is to provide an improved type of scraper or cleaning plate for removing the contents of the 30 bucket when the bucket is in a position for emptying.

Another object of the invention is to provide improved means for swinging the bucket bottoms out of operative position thus permitting them to clear and pass the scraper or cleaning plate.

Another object of the invention is to so 40 construct the wheel that the cleaning plate may extend between the side rings of the wheel, the cam bar for raising the bottom of the buckets being positioned between the side rings of the wheel and having one end connected with the cleaning plate and the other end connected with an arcuate strip 45 positioned between the side rings of the wheel and forming a bucket wall during rotation of the wheel.

Another object of the invention is to so 50 construct the improved wheel that a conventional construction of excavating wheel can be readily converted into the improved construction.

This invention is illustrated in the accompanying drawings, wherein:

55 Figure 1 is a view in side elevation show-

ing the improved excavating wheel in position for use.

Fig. 2 is a top plan view of the structure shown in Fig. 1.

Fig. 3 is a sectional view taken along the 60 line 3-3 of Fig. 1 and showing the improved bucket and cleaning mechanism in end elevation.

Fig. 4 is a sectional view taken along the 65 line 4-4 of Fig. 1.

Fig. 5 is a perspective view of the pivotally mounted section of the bucket.

Fig. 6 is a side elevation of the cleaning blade and cam bar carried thereby.

Fig. 7 is a vertical section on line 7-7 of 70 Fig. 6.

This improved excavating wheel is used in connection with an excavating machine of the type disclosed in the Patent No. 891,000 issued June 16, 1908, and including a frame 75 having side bars 1 which support hanger frames 2. Supporting rollers 3 are carried by the hanger frames 2 and driving pinions 4 are provided and rotatably mounted by means of a shaft 5. A sprocket 6 is mounted upon this shaft and engaged by a sprocket chain 7 so that the shaft 5 and pinions 4 may be rotated from a suitable source of power.

The wheel is provided with side rings 8 which are positioned between the side bars 1 and about the hanger frames 2 and are provided with teeth 8' for engagement by the sprockets 4. It will thus be seen that when the shaft 5 is rotated, the rings 8 will be rotated.

The buckets are positioned about the 90 wheel as shown, and will have outer and side walls, the walls referred to of each bucket being formed from a strip 9 of metal which is secured to the side rings and is curved transversely between the rings. An arcuate strip 10 is connected with the hanger frames by supports 11, and is positioned adjacent the inner edges of the rings 8, thus forming an inner wall for the buckets as the wheel rotates.

An arcuate strip 10 is connected with the hanger frames by supports 11, and is positioned adjacent the inner edges of the rings 8, thus forming an inner wall for the buckets as the wheel rotates.

It will thus be seen that when a bucket is in the position shown at the left of Fig. 1, the transversely curved strip 9 will form the outer wall which merges into the side walls, the side walls being partly formed by the rings 8. This strip 10 extends from a point adjacent the lower side of the wheel to a point above the hopper 12 beneath which is mounted the endless conveyer 13.

This endless conveyer extends 100 transversely of the wheel and will receive 110

the material carried upwardly by the bucket. In the present illustration, the wheel has been shown with four buckets, but it is to be understood that a wheel may be provided 5 with any suitable number of buckets according to the size of the wheel.

A cleaning plate or blade 14 is secured to the hopper or conveyer frame and extends upwardly between the side rings 8 of the 10 wheel to a point above the wheel, as shown in Fig. 1, thus providing a device over which the buckets will pass as the wheel rotates and which will remove clay, mud or other material therefrom.

15 Each bucket has a movable bottom, end plate or wall 15, provided with arms 16 which extend forwardly beyond the front end of the bucket and are pivoted to the blades 17. The blades 17 are secured to the rings 8 and 20 have sharpened edges to truly and smoothly cut the sides of a ditch. A curved strip 18, secured to the arms 16 adjacent the blades 17 and provided with teeth 19 constitutes a digging or cutting element at the forward or 25 advance end of each bucket.

When this device is in use, the wheel extends into the ditch or trench which is being formed and rotates with the buckets moving upwardly out of the ditch in engagement 30 with the end of the ditch. As they move upwardly, the teeth 19 engage the end wall of the ditch and cut the earth from the same. This earth will fall into the buckets and will be held therein by the strip 9 forming the 35 outer and side walls, the arcuate strip 10 forming an inner wall, and the bottom 15.

It should be noted that the pressure upon the teeth during the cutting process operates to swing the arms 16 inwardly, and therefore the bottom 15 will be securely held in an operative position. When the bucket moves to a position beyond the upper end of the arcuate strip 10 to a position above the hopper 12 and endless conveyer, it is desired to 40 have the bottom 15 move to a raised or inoperative position thus permitting the cleaning plate 14 as the bucket moves over it, to scrape the contents out of the same, so that the earth or other material filling the bucket, 45 will drop into the hopper and upon the endless conveyer. Therefore, a curved bar, strip or element 20 which forms a cam, is positioned as shown in Fig. 1 with one end secured to the upper end portion of the strip. 50 50 and the other end portion connected with the upper end of the plate 14 and extending beyond the same a short distance. The bottom 15 engages this cam bar and as the wheel rotates the bottom side bars 16, carrying the 55 bottom, will be swung upwardly to a raised position, thus permitting the bucket to pass the plate 14 and the bottom to clear the plate. The contents of the bucket will thus be scraped therefrom and will drop upon the 60 bottom, will be swung upwardly to a raised position, thus permitting the bucket to pass the plate 14 and the bottom to clear the plate. The contents of the bucket will thus be scraped therefrom and will drop upon the 65 endless conveyer. As soon as the bucket has

passed beyond the end of the cam bar, the weight of the bottom will cause the arms to swing down to the original position and the bucket is again in an operative position. It will thus be seen that as the wheel rotates the earth will be dug from the end of the trench or ditch, and further, the blades 17 will serve to cut the side walls of the trench, thus producing a trench which will be of an even width throughout its length and depth. 70

I claim:

1. A trench digging wheel having spaced side rings, a support for rotatably mounting the wheel including rollers engaging said rings, an arcuate strip carried by the support and positioned to one side of the wheel adjacent the inner peripheries of the rings and extending from a point adjacent the lower end of the support to a point above the upper end thereof, a conveyer extending transversely of the wheel above the support and within the wheel, open-ended buckets carried by the wheel and connected with the rings and spanning the space between the same, cutting blades carried by the rings in advance of the open-ended buckets, bottoms for the buckets, arms extending from the bottoms and connected with the cutting blades to mount the bottoms for swinging movement into and out of an operative position, strips carried by the arms between the buckets and cutting blades and having cutting teeth, a scraping blade extending above the conveyer for passing through the bucket as the wheel rotates, and a strip connected with the arcuate strip and extending above the conveyer and connected with the upper end portion of the scraping blade and constituting a cam for engaging the bottoms of the buckets and swinging the same upwardly out of engagement with the scraping blade as the wheel rotates. 90

2. A digging wheel of the character described comprising side rings positioned in spaced relation, a support for the wheel including rollers having engagement with the inner peripheries of the side rings, a conveyer structure extending through the upper portion of the wheel beneath the side rings, a scraping blade carried by the conveyer structure and extending between the side rings, an arcuate strip carried by the support to one side thereof, a cam strip having one end connected with the arcuate strip and the other end portion with the upper part of the scraping blade, buckets carried by the side rings and open at their ends, cutting blades carried by the side rings, end plates for the buckets having side arms extending upon opposite sides of the buckets and connected with the cutting blades for swinging movement, and cutting strips carried by the side arms and positioned between the cutting blades of the side rings and the open forward ends of the buckets. 110

3. In a structure of the character described, a wheel rotatably mounted and having side rings positioned in spaced relation, an arcuate strip extending circumferentially of the wheel adjacent the inner peripheries of the side rings, open-ended buckets carried by the side rings, a bottom plate for each bucket, arms extending from the bottom plates and pivotally mounted for swinging movement of said plates, a scraping blade extending between the side rings in the path of the bucket, and a cam strip extending circumferentially of the wheel between the side rings for engaging the bottom plates and moving them to a raised position as they pass the scraping blade.

4. In an excavating device of the character described, a supporting structure, a wheel rotatably carried by the supporting structure and including side rings in spaced relation, a scraping blade extending between the rings, a cam strip extending circumferentially of the wheel from the scraping blades between the side rings, an open-ended bucket carried by the side rings, cutting blades carried by the side rings in advance of the open-ended bucket, and a bottom plate for the rear end of the bucket having side arms pivotally connected with the cutting blades for swinging movement of said plates, the cam strip engaging the bottom plate and moving the same upwardly

to clear and pass the scraping blades as the wheel rotates.

5. An excavating device including a support, a wheel rotatably carried by the support, an open-ended bucket carried by the wheel, a scraping blade over which the bucket passes as the wheel rotates, a cam element, and a bottom plate for the rear end of the bucket mounted for swinging movement and diversion by the cam element as the wheel rotates, the cam element moving the bottom plate into position to clear the scraping blade as the wheel rotates.

6. In an excavating device a rotatable wheel, open-ended buckets carried by the wheel, a scraper over which the buckets pass as the wheel rotates, a cam, and bottom plates for the rear ends of the buckets mounted for swinging movement into and out of an operative position, the cam adapted to move the bottom plates into position to clear and pass the scraper as the wheel rotates.

7. An excavating device including a rotatable wheel, open-ended buckets carried by the wheel, a bottom plate for each bucket, arms pivotally connecting the bottom plates with the wheel, and cutting blades carried by the arms in advance of the buckets.

In testimony whereof I have hereunto set my hand.

HOWARD S. BROWN.
